[57] **CLAIM**

The ornamental design for a fifth wheel hitch, as shown and described.

DESCRIPTION

FIG. 1 is a rear perspective view of a fifth wheel hitch showing my new design.

FIG. 2 is an enlarged right side elevational view thereof, the opposite side being substantially a mirror image of that shown;

FIG. 3 is an enlarged front elevational view thereof; and

FIG. 4 is an enlarged top plan view thereof.

FIG. 1.

FIG. 2.
